(57) **CLAIM**

The ornamental design for a combined lighting fixture and motion sensor, as shown and described.

DESCRIPTION

FIG. 1 is a perspective view of a combined lighting fixture and motion sensor in accordance with the new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view thereof, showing the lighting fixture rotated upward;

FIG. 9 is a perspective view thereof, showing the lighting fixture rotated downward; and,

FIG. 10 is a perspective view thereof, showing the motion sensor and lighting fixture rotated to the left.
